UNITED STATES PATENT OFFICE.

ARTHUR O. HUBBARD, OF MINNEAPOLIS, MINNESOTA; NELLIE H. HUBBARD, EXECUTRIX OF SAID ARTHUR O. HUBBARD, DECEASED, ASSIGNOR TO PUFFER-HUBBARD MANUFACTURING COMPANY, OF MINNEAPOLIS, MINNESOTA, A CORPORATION OF MINNESOTA.

METAL CLOTHES WRINGER.

Application filed November 28, 1921. Serial No. 518,360.

To all whom it may concern:

Be it known that I, ARTHUR O. HUBBARD, a citizen of the United States, resident of Minneapolis, county of Hennepin, State of Minnesota, have invented certain new and useful Improvements in Metal Clothes Wringers, of which the following is a specification.

The object of my invention is to simplify 10 and improve the metal wringer shown and described in my application for Letters Patent of the United States, Serial No. 383,442, filed May 22, 1920 issued November 13, 1923, #1,473,769.

15 A further object is to provide a wringer of comparatively few parts which can be easily and quickly assembled.

The invention consists generally in various constructions and combinations, all as 20 hereinafter described and particularly pointed out in the claims.

In the accompanying drawings forming part of this specification,

Figure 1 is a side elevation of a metal 25 clothes wringer embodying my invention,

Figure 2 is a vertical transverse sectional view of the same,

Figure 3 is a longitudinal sectional view 30 showing the relative arrangement of the wringer rolls and bearings,

Figure 4 is an end view of the wringer,

Figure 5 is a sectional view on the line 5—5 of Figure 3.

In the drawings, the wringer frame is 35 shown composed of forward and rear metallic sections having their abutting faces fitting snugly together and secured by bolts or other suitable means. These sections I will designate broadly by reference letters

40 A and B. Specifically, each section comprises an arched middle portion 2 integral with end rails 3 and 3^a joined together across the front and rear of the frame by integral webs 4. Integral strengthening and

45 finishing ribs 5 are joined to the upper portion of the rails 3 on both sides and extend along curved lines to the upper edges of the webs 4 and there merge into horizontal lips 5^a which form an upward extension of the 50 webs 4 and have outwardly and downwardly inclined surfaces 6 in the front and rear of the wringer rolls.

The rail 3 is provided with outwardly projecting lugs 7 on the front and rear sections and a bolt 8 passes through these lugs 55 and through the upper portion of a housing 9 for securing the wringer frame thereto. Mechanism is provided within this housing for operating the rolls, as will hereinafter appear. Bolts 10 and 10^a connect the forward and rear sections of the rails 3 and 3^a for clamping them securely together and bolts 11 and 12 pass through the arched top portions or sections A and B for clamping them together. Lugs 13 depend from the lower portion of the rail 3, a clamping bolt 14 passes through these lugs and a bolt 15 is loosely pivoted thereon at one end and adjustably connected at its opposite end with a bracket 16 on the lower portion of 70 the housing 9, thus providing means for clamping the housing and the wringer frame firmly together. Lugs 17 and 17^a depend from the lower portions of the rails 3 and 3^a and bolts 18 pass through these 65 lugs and aid in clamping the lower portions of the wringer sections together. The lugs 13 and 17 are preferably connected by webs 13^a.

The wringer frame sections are hollow, as 80 indicated in Figure 3, and the rail 3 has an extension housing 19 thereon integral with the remaining portion of the frame, preferably, and wider, as indicated in Figures 1 and 4, to provide room for the operation of the wringer roll gears. A space 20 is provided within the housing 19 for these gears and integral ribs 21 formed on the inner walls of the rail sections 3 separate this space from chamber 22, a corresponding 90 chamber 22^a being provided at the other end of the wringer frame in the rail section 3^a.

In the lower portion of these chambers 22 and 22^a, blocks 23 of suitable material, 95 such as wood, are seated, having bearings for a shaft 24 on the lower wringer roll 25. The upper wringer roll 26 has a shaft 27 and blocks 28 are arranged in the chambers 22 and 22^a to bear on the shaft 27 and slide vertically in the guideways in said chambers 22 and 22^a formed by the ribs 21 and the walls of the wringer rails. The shaft 24 has a squared extension 29 which projects

through the wall of the wringer frame and is adapted for connection with a suitable source of power (not shown).

Upon the shafts 24 and 27 driving gears 30 are mounted, those on the shaft 27 meshing with the gears on the shaft 24 to be driven thereby when the rolls are in their working relation. A spring plate 31 is arranged to bear on the blocks 28 and a bar 32 is pivoted at one end on the bolt 11 and carries a screw 33 that is arranged to contact with the middle portion of the spring 31 and exert a downward pressure thereon. A lever 34 is pivoted on the bolt 12 and has a jaw 35 arranged to engage a lug 36 on the end of the bar 32 and is normally held in said engagement by the tension of a spring 37. A lug 38 on the lower portion of the lever 34 engages a stop 39 and limits the upward movement of the lever 34 when it is released from engagement with the bar 32. Evidently, when this bar is in its horizontal locking position, pressure will be applied through the screw 33 to the spring 31 to force the rolls together and hold them with a yielding pressure, the degree of which will depend upon the adjustment of the screw. When the lever 34 is tripped, the bar will immediately be released and the rolls allowed to separate.

The lugs 17 and 17^a support brackets 40 and said brackets are connected by a rod 41. A drip plate 42 has depending flanges 43 recessed at 44 to receive the rod 41 and slide thereon, the shoulders in the flanges 43 at the ends of the recess 44 limiting the sliding movement of the drip plate thereon. The ends of the drip plate are folded upwardly and downwardly, as indicated at 45, to present a rounded, smooth effect, corresponding substantially to the surface of a roller, and ports 46 are provided in the drip plate near these rounded portions, through which the drippings from the clothes may escape. Above the drip plate upwardly projecting flanges 47 are provided and these are preferably vertical extensions of the flanges 43, which are preferably pressed from sheet metal seated against the underside of the drip plate 42 and secured thereto by suitable means, such as rivets 48. The flanges 47 preferably have notches 49 near their middle portion and latches 50 are mounted in pairs on the front and rear of the sections A and B and are adapted to slip into the notches 49 and lock the drip plate in its tilted position, either forwardly or backwardly, as indicated by full and dotted lines in Figure 4.

The drip plate may be removed entirely from the wringer by disengaging the latches 50 from the notches in the flanges 47. There are, therefore, only three pieces to this drip plate—the main portion of the plate having the roller-like folds at the ends, and the two flanged members secured to the ends of the drip plate and projecting above and below it, as indicated in Figure 2.

As shown in Figure 2, the webs 4 extend in under the lower wringer roll, being separated by a gap 51 through which the water 70 may flow from the rolls down upon the drip plate, being guided thereto by the curvature of the webs 4.

I claim as my invention:

1. A clothes wringer comprising two corresponding metallic members fitting one against the other and means for securing them together, said members comprising end rails and integral arched portions between them, integral webs horizontally connecting the lower ends of said rails, and having inwardly and downwardly curved portions, integral ribs extending inwardly and downwardly from the upper portions of said rails and merging into the upper edges of said webs, and upper and lower wringer rolls mounted in said rails between said ribs and webs.

2. A clothes wringer comprising two corresponding metallic members fitting one against the other and means for securing them together, said members including end rails and arched integral middle portions between them, integral webs connecting the opposite lower portions of said end rails and having inwardly and downwardly curved portions with a narrow longitudinal gap between them, and upper and lower wringer rolls mounted in said rails above said gap.

3. A clothes wringer comprising two corresponding metallic members fitting one against the other and means for securing them together, said members including end rails and arched integral middle portions between them, integral webs connecting the opposite lower portions of said end rails and having inwardly and downwardly curved portions with a longitudinal gap between them, the upper edges of said webs being flanged and having outwardly and downwardly inclined surfaces thereon, and upper and lower wringer rolls mounted in said rails above said webs.

In witness whereof, I have hereunto set my hand this 22d day of November, 1921.

ARTHUR O. HUBBARD.
